Application December 16, 1941, Serial No. 423,196

17 Claims. (Cl. 82—2)

The present invention relates to a machine method and cutter for forming or cutting material such as metal, plastics, wood, etc.

The principal object of the invention is the provision of a novel and improved method of forming or cutting material such as metal, plastics, and the like, wherein a work blank is rotated in cutting relation with a disk-like or sector-like tool having a cutting edge portion or portions along the circumference or arcuate edge thereof rotated either continuously or intermittently about an axis angularly disposed and offset with respect to the axis of rotation of the work blank while a relative movement between the tool and work blank is effected longitudinally of the axis of rotation of the work blank and tool are so positioned that a plane or planes at right angles to the axis of rotation of the tool and passing through a cutting portion or portions of the tool are substantially tangent to the work blank.

Another object of the invention is the provision of a novel and improved method of forming or cutting material such as metal, plastics, and the like wherein a work blank is rotated in cutting relation with a disk-like or sector-like tool having axially offset arcuately shaped cutting edge portions along the circumference thereof rotated either continuously or intermittently about an axis angularly disposed and offset with respect to the axis of rotation of the work blank while a relative movement between the tool and work blank is effected longitudinally of the axis of rotation of the work blank and wherein the tool and work blank are so positioned that a plane or planes at right angles to the axis of rotation of the tool and passing through a cutting portion or portions of the tool are substantially tangent to the work blank.

Another object of the invention is the provision of a novel and improved machine for forming or turning material such as metal, plastics, and the like, wherein the work blank is rotated in cutting relation with a disk-like or sector-like tool having a cutting edge portion or portions along the circumference or arcuate edge thereof rotated either continuously or intermittently about an axis angularly disposed and offset with respect to the axis of rotation of the work blank while a relative movement between the tool and work blank is effected longitudinally of the axis of

rotation of the work blank and wherein the work blank and tool are so positioned that a plane or planes at right angles to the axis of rotation of the tool and passing through a cutting portion or portions of the tool are substantially tangent to the work blank.

Another object of the present invention is the provision of a novel and improved disk-like or sector-like tool or cutter for turning or cutting material such as metal, plastics, and the like, when rotated either continuously or intermittently in cutting relation with a rotating work blank with its axis of rotation angularly disposed and offset with respect to the axis of rotation of the work blank and in such position that a plane normal to its axis of rotation and passing through a cutting portion thereof is substantially tangent to the work blank, while a relative feed movement between the tool and work blank is effected longitudinally of the axis of rotation of the work.

Another object of the present invention is the provision of a novel and improved disk-like or sector-like tool or cutter having axially spaced cutting portions for turning or cutting material such as metal, plastics, and the like, when rotated either continuously or intermittently in cutting relation with a rotating work blank with its axis of rotation angularly disposed and offset with respect to the axis of rotation of the work blank and in such position that a plane normal to its axis of rotation and passing through a cutting portion thereof is substantially tangent to the work blank, while a relative feed movement between the tool and work blank is effected longitudinally of the axis of rotation of the work blank.

The present invention resides in certain details of construction and combinations and arrangements of parts, and further objects and advantages of the invention will be apparent to those skilled in the art to which the invention relates from the following description of the preferred embodiment thereof described with reference to the accompanying drawings forming a part of the specification and in which

Generally speaking, the method of the present invention contemplates rotating a work blank in cutting relationship with a segmental tool or cutter slowly rotated either continuously or intermittently about an axis at or substantially at right angles to the axis of rotation of the blank and offset therefrom, with the tool engaging the work in such a manner that the cutting thrust produced thereby is substantially at right angles to the axis of rotation of the tool while producing a relative feed movement between the blank and the tool in a direction longitudinally of the axis of rotation of the blank. When it is desired to cut portions of different diameter on the work blank, these portions are cut by axially spaced cutting portions on the tool.

While the invention is susceptible of embodiment in various modifications and alternative constructions, it is herein shown and described as embodied in a vertical type machine wherein the work is rotated about a vertical axis in cutting relation with a segmental type tool rotated about a horizontal axis at right angles to the axis of rotation of the work, and wherein a relative feed movement is effected between the work and tool in a direction longitudinally of the axis of rotation of the work. The tool or cutter is frusto-conical in shape with the cone axis coincident with the axis of rotation, and the base, which in operation is adjacent to the work, has axially offset portions since the 75 mm. shell which the cutter illustrated is designed to turn has portions of different diameter. However, it is to be understood that if the tool is designed to produce an article of uniform diameter, the cutting edges or portions of the tool will lie in the same plane; in other words, the working portions of the circumference of the segment which forms the tool will lie in the same plane. The speed of rotation of the work blank is preferably, but not necessarily, varied as different axially spaced portions of the cutter engage the blank so that the cutting operation is always performed at the maximum cutting speed consistent with other requirements, thereby obtaining maximum production.

Referring to the drawings, the machine shown therein comprises a base A and a vertical hollow

column B upon which is slidably supported for vertical movement a work head C through the medium of vertically spaced ways 10 and 11. The tool head D is adjustably supported for movement in a horizontal plane in a cylindrical aperture 12 intermediate the ways 10 and 11. The work blank W, in the present instance, a 75 mm. shell, is supported by a chuck 13 fixed to the upper end of the work spindle 14 and a center 15 carried by a tailstock 16 slidably supported on vertical ways 17 and 18 formed on the work head C. The tailstock 16 is adapted to be moved vertically and clamped and unclamped to the ways 17 and 18 by a single operating lever 19, the construction and operation of which are well known in the art. The lower end of the work blank W, which is the nose of the shell, is hollow and the work blank is chucked to the chuck 13 through the medium of an expandable mandrel M, the construction of which forms no part of the present invention.

The tool T which is semi disk-like or segmental in shape is carried by a horizontal tool spindle 20 rotatably supported in the tool head D and during the cutting operation is slowly rotated about its axis as the work is fed vertically past the same. In the embodiment shown, the work or shell W has a tapered base and nose 21 and 22, respectively, and two intermediate cylindrical sections 23 and 24 of different diameters and accordingly the tool has four axially spaced cutting edges or portions a, b, c, and d, the first and last of which are inclined. The work spindle 14 is driven by a multi-speed electric motor 25, called the cut motor, the speeds of which are so adjusted that maximum cutting speed in feet per minute consistent with other conditions, such as, the character of material being turned, the kind of tool employed, the rate of feed, etc., is maintained irrespective of the diameter of the work being turned at any particular time. In the embodiment illustrated, only one speed is employed since the variations in the diameter of the different portions of the work are not great. As shown, the vertical movement of the work head C which effects the feed is produced by a cooperating lead screw 26 and nut 27, the former of which is driven from the work spindle, which assures a definite relationship between the speed of rotation of the work and the rate at which it is fed past the cutter. A high speed reversible electric motor 28, called the traverse motor, operatively connected to the nut 27 provides means for rapidly moving the work head C to bring the work up to the tool at the beginning of the cycle of operations and for returning the work head to its starting position after the blank has been turned and removed.

The machine is started by pressing a start button 29, which closes a circuit to the traverse motor 28, causing the same to rotate the nut 27 to move the work head upwardly at a rapid rate. Just prior to the engagement of the work with the tool, an adjustable stop 30 carried on a bar 31 fixed to the top of the work head C actuates a switch 32, stopping the traverse motor 28 and starting the cut motor 25. Thereafter the work head C continues to move in an upward direction but at a feed rate. If the diameters of the different portions of the work vary greatly, the speed of the motor 25 can be automatically varied as different portions of the work reach the cutting position by a plurality of adjustable stops 33, 34, 35, and 36 carried by a plate 37 fixed to the work head C. These stops actuate suitable

electric speed selection switches 38, 39, 40, and 41 fixed to the upper part of the column B and connected in the control circuit in a manner hereinafter described.

After the cutting operation is completed, the circuit to the cut motor 25 is opened upon the actuation of a travel limit switch 42 by an adjustable stop 43 on the bar 31, whereupon the machine stops and the blank is removed. When the start button 29 is again depressed, the traverse motor 28 operates in the reverse direction to return the work head C to starting position. In order to increase the flexibility of the machine, the control for the cut motor 25 preferably comprises a drum controller, designated generally by 15 the reference character E, through the medium of which control circuits for the motor can be so selected that the motor will go through a cycle of various speeds automatically or any one of its various speeds can be selected. In the latter event, which is the case in the present instance, the selected speed alone will operate during the entire cutting operation. In addition to the automatic position, designated "Auto," and the four different speed positions, designated "1," "2," "3," and "4," the drum controller E also has an off position, designated "Off."

The cut motor 25 is located within the column B but is fixed to and carried by the work head C through the medium of a bracket 44. The armature shaft 45 of the motor 25 is connected to a short shaft 46 by a coupling 47, which shaft is rotatably supported in the work head C and is provided with a small gear 48 fixed thereon continuously in mesh with a large gear 49 fixed to a shaft 50 also rotatably supported in the work head C. The shaft 50 projects into a gear compartment 51 in the lower front part of the work head C where it is operatively connected to a short shaft 52 through the medium of gears 53 and 54. The shaft 52 is rotatably supported in the work head C and is provided at the left-hand end, as viewed in Figs. 3 and 4, with a bevel gear 55 continuously in mesh with the bevel gear 56 fixed to the work spindle 14. The gear compartment 51 is adapted to be closed by a removable cover 57, and the gears therein are preferably operated in oil.

The lead screw 26 is rotatably supported in the work head C against axial movement and is rotated at a relatively slow speed and in timed relation to the rotation of the work spindle 14 to effect the feed movement of the work head C by the cut motor 25 to which it is operatively connected by a worm wheel 58 fixed to its upper end, which worm wheel is continuously in mesh with a worm 59 keyed on a horizontal shaft 60 rotatably supported in the work head C. The shaft 60, like the shaft 50, projects through the partition 61 in the work head C and the left-hand end thereof, see Fig. 4, is provided with a gear 62 in mesh with a gear 63 fixed to the shaft 52 to the left of the gear 54.

As previously stated, the nut 27 with which the lead screw 26 cooperates is adapted to be rotated at a high rate of speed to produce a rapid-traverse movement of the work head C in either direction by the traverse motor 28, the armature shaft 64 of which is connected by a coupler 65 to a short shaft 66 rotatably supported in a bracket 67 which supports the nut 27. The shaft 66 is provided with a worm, not shown, continuously in mesh with a worm wheel 68 formed about the circumference of the nut 27. The lead screw 26 is preferably provided with a telescopic guard,

designated generally as 69, which prevents the entrance of chips, etc., into the interior of the bracket 67.

The tool spindle 20 is rotatably supported in a cylindrically-shaped tool head D slidably but non-rotatably secured in the aperture 12 in the column B intermediate the ways 10 and 11. The tool head is adapted to be adjusted towards and from the axis of rotation of the work spindle 14 by a lead screw 70 rotatably supported in the column B and continuously in mesh with a nut 71 fixed to the cylindrical rear end of the tool head. The lead screw 70 is provided with a micrometer dial 72 at the front end thereof, which end projects through the column B. The tool head can be clamped in any position to which it is adjusted by a pair of clamps 73 and 74 adapted to be moved towards or from each other by a shaft 75 projecting through the clamp member 73 and having threaded engagement with the clamp member 74. As shown in Figs. 1, 2 and 3, the tool head D is retracted from operating position in the interest of clearness, but it is to be understood that during operation the tool head is advanced to bring the tool T into proper cutting position with respect to the work W.

As the work head C moves vertically, the tool spindle 20 and, in turn, the tool or cutter T is rotated slowly by a cam plate 76 bolted or otherwise detachably connected to the work head C, which cam plate has a cam slot 77 therein within which a cam roller 78 engages. The cam roller 78 is adjustably fixed to a rack bar 79 slidably supported in an extension 80 of the tool head D. The rack teeth 81 of the rack bar 79 are continuously in mesh with a gear 82 fixed to the left-hand end of the tool spindle 20. To provide an adjustment between the roller 78 and the rack bar 79, the roller is mounted on a short shaft 83 fixed in a movable block or member 84 slidably supported in a suitable aperture 85 formed in the rack bar 79. The block or member 84 is adapted to be moved relative to the rack bar 79 by a screw 86 having threaded engagement with the member 84 and rotatably supported against axial movement in the rack bar 79. In order to eliminate back-lash in the mechanism operatively connecting the tool spindle 20 to the cam plate 76, the tool spindle is continuously urged in a clockwise direction, as viewed in Fig. 8, by an air motor 87 located within the column B, the piston rod 88 of which is connected by a sprocket chain 89 to a sprocket wheel 90 fixed to the tool spindle 20. The air motor 87 is continuously supplied with air under pressure during the operation of the machine.

As previously stated, the tool or cutter T is frusto-conical in shape, with the cutting edge or edges formed along the circumference 91 of the base or end 92 of greatest radius and is preferably segmental or semi-circular as viewed axially. In other words the tool shown, generally speaking, resembles a segment of a frustum of a right circular cone. In operation, the cutter is positioned with its axis of rotation 93 offset from and angularly disposed with respect to the axis of rotation 94 of the work, the position being such that a plane or planes normal to the axis of rotation of the cutter and passing through the cutting edge or edges is substantially tangent to the work at the point of engagement of the cutter therewith. From the foregoing, it follows that the thrust produced by the cutting operation is largely at right angles to the axis of the tool. During the cutting operation, the tool is slowly

rotated either continuously or intermittently and a relative feed movement is effected between the tool and the work in a direction longitudinally of the axis of the work. When it is desired to produce or turn a work piece having portions of different diameter by a single tool, the cutting portions or edges of the tool which form or cut the various diameters on the work are axially offset with respect to each other.

Referring to the tool and work shown, the tapered base 21 of the shell W, see Fig. 11, is turned by the axially inclined cutting edge a of the tool. The cylindrical portions 23 and 24 of the shell are turned by the axially offset cutting edges b and c and the tapered or rounded nose 22 of the shell is turned by the axially inclined cutting edge d of the tool. In the embodiment shown, the length of the cutting edges of the tool is less than the length of the work being turned and the tool is continuously rotated during the cutting operation in the direction indicated by the arrow 95 in such a manner that the tool rolls with slip along the shell. This arrangement allows long work pieces to be turned by tools of convenient size. A cylindrical section can be turned without rotating the tool but when turning a curved or irregular surface, some rotation must be imparted to the tool. In some instances it may be desired to stop the relative longitudinal feed movement temporarily and merely rotate the tool. As will be apparent to those skilled in the art, the amount and speed of the rotation imparted to the tool will be a function of the form of the tool, the speed of the relative longitudinal feed movement between the tool and the work, 35 and the shape of the blank being turned.

The conical shape of the tool provides rake or top slope for the cutting edge or edges. In the tool shown, no so-called clearance angle is provided but it will be apparent that the tool may be formed or provided with a suitable clearance angle if desired. Preferably the tool and work are so positioned that the tool cuts on center but because of its frusto-conical shape, the radius of the cutting edge varies as a function of or in relation to the axial variation of the cutting edge. This variation of the radius of the cutting edge or edges makes it impossible to so position the tool and work that the tool always cuts exactly on center but the variation from center is not sufficient to materially interfere with the operation. If the forms of the tool and work are such that any portion of the tool cuts any considerable distance off center, suitable compensation can be made in the form of the tool or cutting edge to obtain the desired form of work. The correct form can be computed or arrived at by a cut and try method. Alternatively a cutter may be made similar in form to the finished work and used in the machine to produce a blank having the desired cutter form or approximately the desired form. Preferably the tool is so operated that those portions of the cutting edge which do not cut on center cut below center. If desired, provision can be made for automatically shifting the tool axially so that it always cuts on center or a predetermined position with respect thereto.

The cut motor 25 shown is of the four-speed type which allows the spindle to be rotated at any of four different speeds, thus producing a machine which will turn work of different diameters with the cutting operation always being performed at maximum efficiency. It is to be understood, however, that a motor having any

desired number of speeds can be employed. A four-speed motor is selected for purposes of illustration because four speeds are sufficient to accommodate most articles which the present machine is designed to turn.

With the exception of the fact that the tool head is retracted in some of the figures as previously stated, the relative positions of the various parts of the machine at the commencement of a cycle of operations is shown in the drawings. The work head C is at the bottom of its travel and after a work blank W has been positioned in the work head, the machine is started by depressing the start push button switch 29 located 10 on a control panel 96 fixed to the left-hand side 15 of the machine in a position readily accessible to the operator. With the drum controller E set in its "first" position, that is in the position in which the motor operates at its lowest speed, the 20 depressing of the start push button switch 29 closes a circuit from the line 101 through the normally closed stop push button switch 102, line 103, normally open start push button switch 29, line 104, operating solenoid 105 of relay 106, line 107, contacts 108 of travel limit switch 42, line 109, overload contacts 110, line 111, overload contacts 112, line 113, overload contacts 114, line 115, overload contacts 116, line 117, overload contacts 118, line 119, and overload contacts 120 to 134. The overload contacts 110, 112, 114, 116, 118, and 120 are located on a motor control panel 30 in the position shown in the wiring diagram.

Energization of the operating solenoid 105 of relay 106 closes the normally open contacts 122, 123, and 124 thereof and opens the normally closed contacts 125. The closing of contacts 122 establishes a circuit from the line 101 through the normally closed stop push button switch 102, line 103, contacts 122, line 126, operating solenoid 40 127 of rapid-traverse motor control panel 128, line 129, closed contacts 130 of change-over switch 32, line 107, closed contacts 108 of travel limit switch 42, line 109, etc., to 121. Energization of the operating solenoid 127 of the rapid-traverse motor control panel 128 closes the normally open contacts 131, 132 and 133 connecting the rapid-traverse motor 28 to the power lines 101, 134, and 121 in such a manner that the motor operates in a direction to rapidly raise the work head C.

Simultaneously with the closing of contacts 131, 132, and 133 of the rapid-traverse motor control panel 128 normally open contacts 135 on the control panel are closed. These contacts are 55 in parallel circuit with the contacts 122 of relay 106 and establish a holding circuit for the operating solenoid 127, continuing the operation of the rapid-traverse motor 28 after the start push button switch 29 has been released.

The closing of contacts 123 of relay 106 establishes a circuit from the line 101 through the stop push button switch 102, line 103, contact bar 136 of drum controller E, line 137, contacts 123, line 138, operating solenoid 139 of relay 140, line 107, closed contacts 108 of travel limit switch 42 and line 109, etc., to 121. Energization of the operating solenoid 139 of relay 140 closes the normally open contacts 141 and 142 thereof. The contacts 141 are in parallel circuit with the contacts 123 of relay 106 and the closing of these contacts establishes a holding circuit for the operating solenoid 139 of relay 140 after the start push button switch 29 is released. The closing of the contacts 124 of relay 106 and the closing of contacts 142 of relay 140 do not establish any

circuits at this time since these contacts are in series with open contacts 143 of change-over switch 32.

Just prior to the engagement of the work with the tool, the stop 30 actuates the change-over switch 32 to open the closed contacts 130 and close the open contacts 143 thereof. The opening of contacts 130 of change-over switch 32 deenergizes the operating solenoid 127 of rapid-traverse motor control panel 128 disconnecting the rapid-traverse motor 28 from the line and causing the same to stop. The closing of contacts 143 establishes a circuit from the line 101 through the stop push button switch 102, line 103, normally open contacts 142 of relay 140, which contacts are now closed, line 144, contact bar 145 of drum controller E, line 146, operating solenoid 141 of motor control panel 148, line 149, contacts 150 of relay 151, line 152, contacts 143 of change-over switch 32, line 107, contacts 108 of travel limit switch 42 and line 109, etc., to 121.

Energization of the operating solenoid 141 of motor control panel 148 closes the normally open contacts 153, 154, 155, and 156 thereof, connecting the cut motor 25 to the power lines 101, 134, and 121 in such a manner that the motor rotates at its "first" speed. The cut motor 25 continues to operate at its selected speed until the travel limit switch 42 is actuated by the stop 30 to open the normally closed contacts 108 thereof and close the open contacts 157. The opening of the normally closed contacts 108 breaks the circuit to the operating solenoid 141 of motor control panel 148 whereupon the motor comes to rest.

With the work head C in its upper position, the work blank is removed and the work head returned to its initial or starting position by again depressing the start push button switch 29. This establishes a circuit from the line 101 through the stop push button switch 102, line 103, start push button switch 29, line 158, operating solenoid 159 of motor control panel 128, line 160, contacts 157 of travel limit switch 42 and line 109, etc., to 134. Energization of the operating solenoid 159 of motor control panel 128 closes the normally open contacts 161, 162, 163, and 164 thereof. The closing of contacts 161, 162, and 163 connects the rapid-traverse motor 28 to the lines 101, 134, and 121 in such a manner that it rotates in a direction opposite to that in which it rotated when the start push button switch 29 was depressed with the work head in its "down" position. The motor now operates in a direction to lower the work head C. A holding circuit for the operating solenoid 159 is maintained by the closing of contacts 164 which permits the start push button switch 29 to be released without stopping the motor 28. As the work head C moves down, the change-over switch 32 is reset by the stop 30 to again close the contacts 130 and open the contacts 143 thereof. The work head C moves in a downward direction at a rapid-traverse rate until the travel limit switch 42 is actuated by an adjustable stop 97 on the top of the work head C to open the closed contacts 157 and close the open contacts 108 thereof. The opening of contacts 157 breaks the circuit to the operating solenoid 159 of motor control panel 128, stopping the rapid-traverse motor 28 and the closing of contacts 108 returns the electrical circuits to their original position. The cycle of operations can now be repeated by again depressing the start push button switch 29. The machine can be stopped at any time during its cycle of operations by depressing the normally closed

stop push button switch 102. The opening of this switch deenergizes all of the control circuits.

As previously stated, the cut motor 25 is a four-speed motor and the drum controller E has, in addition to the "first" position referred to above and an "off" position, a "second," "third," "fourth," and "automatic" position corresponding with the second, third, and fourth speeds of the cut motor and a position wherein the motor goes through its speeds automatically under the control of the speed selection switches 38, 39, 40, and 41. While the "first" speed only is used in turning the particular work referred to in the present instance, the other speeds are used for turning work of different size and if the work has portions of sufficiently different diameters, two or more of the speeds may be employed to turn the various diameters on the work.

Since the present invention contemplates utilizing more than a single speed of the cut motor 25 under certain circumstances, a cycle of operations employing all four speeds of the motor will be herein described. Assuming that the speed selection switches 38, 39, 40 and 41 are properly positioned for the particular work which it is desired to cut and with the drum controller E set at "auto," depressing of the start push button switch 29 establishes a circuit from line 101 through normally closed stop push button switch 102, line 103, normally open start push button switch 29, line 104, operating solenoid 105 of relay 106, line 107, contacts 108 of a travel limit switch 42, line 109, etc., to 121.

Energization of the operating solenoid 105 of relay 106 closes the normally open contacts 122, 123, and 124 and opens the normally closed contacts 125 thereof. The closing of the contacts 122 establishes a circuit from the line 101 through the normally closed stop push button switch 102, line 103, contacts 122, line 126, operating solenoid 127 of rapid-traverse motor control panel 128, line 129, closed contacts 130 of change-over switch 32, line 107, closed contacts 108 of travel limit switch 42, line 109, etc., to 121. Energization of operating solenoid 127 of rapid-traverse motor control panel 128 closes the normally open contacts 131, 132, and 133, connecting the rapid-traverse motor 28 to the power lines 101, 134, and 121 in such a manner that the motor is operated in a direction to rapidly raise the work head C.

Simultaneously with the closing of contacts 131, 132, and 133 of the rapid-traverse motor control panel 128, normally open contacts 135 on the same panel are closed, establishing a holding circuit for the operating solenoid 127 continuing the operation of the rapid-traverse motor 28 after the start push button switch 29 is released. The closing of the contacts 123 of relay 106 establishes a circuit from the line 101 through the stop push button switch 102, line 103, contact bar 136 of drum controller E, line 137, contacts 123, line 138, operating solenoid 139 of relay 140, line 107, closed contacts 108 of travel limit switch 42, line 109, etc., to 121. Energization of the operating solenoid 139 of relay 140 closes the normally open contacts 141 and 142. The contacts 141 establish a holding circuit for the operating solenoid 139 of relay 140 maintaining the solenoid energized after the start push button switch 29 is released.

Just prior to the engagement of the work with the tool, the stop 30 actuates the change-over switch 32 to open the closed contacts 130 and close the open contacts 143. The opening of contacts 130 deenergizes the operating solenoid 127 of rapid-traverse motor control panel 128

disconnecting the rapid-traverse motor from the line and allowing the same to stop. The closing of contacts 143 establishes a circuit from the line 101 through the stop push button switch 102, line 103, normally open contacts 142 of relay 140, which contacts are now closed, line 144, contact bar 145 of drum controller E, line 165, operating solenoid 166 of relay 167, line 152, closed contacts 143 of change-over switch 32, line 107, closed contacts 108 of travel limit switch 42, line 109, etc., to line 121.

Energization of the operating solenoid 166 of the relay 167 closes the normally open contacts 168, 169 and 170. This establishes a circuit from the line 101 through the stop push button switch 102, wire 103, closed contacts 142, line 144, contact bar 145, line 171, normally closed contacts 172 of speed selection switch 40 which also includes normally open contacts 173, line 174, contacts 168, line 175, normally closed contacts 176 of speed selection switch 41 also having normally open contacts 177, line 178, contacts 169, line 179, contacts 170, line 180, normally open contacts 181 of speed selection switch 38, which contacts are now closed by the stop 33 on the plate 31, line 104, operating solenoid 105 of relay 106, line 107, closed contacts 108 of travel limit switch 42, line 109, etc., to line 121. This circuit again closes the normally open contacts of relay 106, contacts 124 of which establish a circuit from the line 138, closed contacts 124 of relay 106, line 146, operating solenoid 147 of motor control panel 148, line 149, normally closed contacts 150 of relay 151, line 152, closed contacts 143 of change-over switch 32, line 107, closed contacts 108 of travel limit switch 42, line 109, etc., to line 121.

Energization of the operating solenoid 147 of motor control panel 148 closes the normally open contacts 153, 154, 155, and 156 thereof, connecting the motor 25 to the power lines 101, 134, and 121 in such a manner that the motor rotates at its "first" speed. Simultaneously with the closing of contacts 153, 154, 155, and 156 of motor control panel 148, normally open contacts 182 are also closed. These contacts establish a holding circuit for the operating solenoid 147 after the speed selection switch 38 is opened upon movement of the stop 33 away from the operating arm thereof. This holding circuit is from the line 101 through stop push button switch 102, line 103, closed contacts 142 of relay 140, line 144, contact bar 145 of drum controller E, line 171, normally closed contacts 172 of speed selection switch 40, line 174, closed contacts 168 of relay 167, line 175, normally closed contacts 176 of speed selection switch 41, line 178, contacts 169, line 179, contacts 170, line 180, contacts 182, line 146, operating solenoid 147, line 149, normally closed contacts 150, line 152, closed contacts 143, line 107, closed contacts 108, line 109, etc., to line 121.

The operating solenoid 183 of relay 184 is in parallel circuit with the operating solenoid 147 of motor control panel 148 and the relay is actuated simultaneously with the contacts of the motor control panel 148 to open the normally closed contacts 185 thereof. The contacts 185 of relay 184 are in series circuit with the operating solenoids of the motor control panels, herein-after referred to, which cause the motor 25 to operate at its "third" speed and the opening of these contacts makes certain that these operating solenoids will not be simultaneously energized with the solenoid 147 of motor control panel

148 which causes the motor to operate at its "first" speed.

The machine continues to operate with the cut motor 25 rotating at its "first" speed until the stop 34 closes the contacts 186 of the speed selection switch 39, whereupon a circuit is established from the line 101 through the stop push button switch 102, line 103, closed contacts 142 of relay 160, line 144, contact bar 145 of drum controller E, line 171, normally closed contacts 172 of speed selection switch 40, line 174, closed contacts 168 of relay 167, line 175, normally closed contacts 176 of speed selection switch 41, line 178, closed contacts 169 of relay 167, line 179, normally open contacts 186 of speed selection switch 39, line 187, operating solenoid 188 of relay 151, line 189, normally closed contacts 125 of relay 106 which is now deenergized, line 152, closed contacts 143 of change-over switch 32, line 107, closed contacts 108 of travel limit switch 42, line 109, etc., to line 121. Energization of the operating solenoid 188 of relay 151 opens the normally closed contacts 150 and 190 and closes the normally open contacts 191 thereof. The opening of the normally closed contacts 150 of relay 151 opens the circuit through the operating solenoid 147 of motor control panel 148, disconnecting the connections to the motor 25 by virtue of which it operates at its "first" speed. This also deenergizes the operating solenoid 183 of relay 184 allowing the contacts 185 thereof to close.

The closing of the contacts 191 of relay 151, which occurs simultaneously with the opening of contacts 150, establishes a circuit through the operating solenoid 192 of motor control panel 193 from the line 101 through stop push button switch 102, line 103, closed contacts 142 of relay 140, line 144, contact bar 145 of drum controller E, line 171, normally closed contacts 172 of speed selection switch 40, line 174, closed contacts 168 of relay 167, line 175, normally closed contacts 176 of speed selection switch 41, line 178, closed contacts 169 of relay 167, line 179, contacts 191, line 194, operating solenoid 192, line 189, normally closed contacts 125 of relay 106, line 152, closed contacts 143 of change-over switch 32, line 107, closed contacts 108 of travel limit switch 42, line 109, etc., to line 121. Energization of the operating solenoid 192 of the motor control panel 193 closes the normally open contacts 195, 196, 197, and 198 to the power lines in such a manner that the motor continues to operate but at a different speed, herein referred to as the "second" speed. Simultaneously with the closing of the contacts 195, 196, 197, and 198 of motor control panel 193, contacts 199 of the same motor control panel are closed, establishing a holding circuit which maintains the operating solenoid 192 of motor control panel 193 energized after the contacts 186 of speed selection switch 39 have opened by the stop 34 moving clear of the actuating arm of said switch. Operating solenoid 200 of relay 201 is in parallel circuit with the operating solenoid 192 of motor control panel 193 and is energized simultaneously therewith to open the normally closed contacts 202 of said relay, which contacts are in series circuit with the operating solenoid 203 of motor control panel 204 by virtue of which the motor is connected to the power lines in such a manner that it operates at a different speed, herein referred to as its "fourth" speed, thus eliminating any possibility of the operating solenoid 203 being simultaneously energized with the operating solenoid 192.

The machine continues to operate with the mo-

tor 25 rotating at its "second" speed until the speed selection switch 40 is actuated by engagement of the stop 35 with the operating arm thereof. Actuation of this switch by the stop 35 opens the normally closed contacts 172 and closes the normally open contacts 173. The opening of the normally closed contacts 172 of speed selection switch 40 breaks the circuit to the operating solenoid 192 of motor control panel 193, deenergizing the circuits by virtue of which the motor operates at its "second" speed. The operating solenoid 200 of relay 201 which is in parallel circuit with the operating solenoid 192 of motor control panel 193 is deenergized at the same time, allowing the normally closed contacts 202 of said relay to close. The closing of contacts 173 of speed selection switch 40 establishes a circuit from the line 101, through the stop push button switch 102, line 103, contacts 142 of relay 140, line 144, contact bar 145 of drum controller E, line 171, contacts 173 of speed selection switch 40, line 205, normally closed contacts 206 of motor control panel 193, line 207, normally closed contacts 185 of relay 184, line 208, normally closed contacts 209 of motor control panel 204, line 210, operating solenoid 211 of motor control panel 212, line 213, normally closed contacts 190 of relay 151, line 189, normally closed contacts 125 of relay 106, line 152, closed contacts 143 of change-over switch 32, line 107, closed contacts 108 of travel limit switch 42, line 109, etc., to line 121. The contacts 206 of motor control panel 193, which are now closed, were opened while the motor was operating at its "second" speed, thus preventing any possibility of the operating solenoid 211 of motor control panel 212 being energized simultaneously with the energization of the operating solenoid 192 of the motor control panel 193 by virtue of which the motor is caused to operate at its "second" speed. In like manner the contacts 209, which are now closed, will be open when the motor is operating at its "fourth" speed, thus preventing simultaneous energization of the operating solenoid 211 of motor control panel 212 with the operating solenoid 203 of motor control panel 204.

Energization of the operating solenoid 211 of motor control panel 212 closes the normally open contacts 214, 215, 216, 217, and 218 thereof. The closing of the normally open contacts 217 establishes a circuit from the line 210 through the contacts 217, line 219, operating solenoid 220 of motor control panel 221 to line 213. As previously stated, energization of the operating solenoid 211 of motor control panel 212 closes the normally open contacts 214, 215, and 216 and the energization of the operating solenoid 220 of the motor control panel 221 closes the normally open contacts 222, 223, and 224 thereof. The closing of the contacts 214, 215, 216, 222, 223, and 224 connects the motor 25 to the power lines in such a manner that the motor operates at a different speed than heretofore, which speed is herein referred to as the "third" speed. The closing of normally open contacts 218 of motor control panel 212 establishes a holding circuit around the contacts 173 of speed selection switch 40. This maintains the operating solenoids 211 and 220 of the motor control panel 212 and 221, respectively, energized after the contacts 173 have opened upon movement of the stop 35 away from the actuating mechanism of the speed selection switch 40.

The machine continues to operate with the motor rotating at its "third" speed until the

speed selection switch 41 is actuated by engagement of the stop 36 with the operating arm thereon. Actuation of this switch by the stop 36 opens the normally closed contacts 176 and closes the normally open contacts 177. The closing of the normally open contacts 177 establishes a circuit from the line 101 through the stop push button switch 102, line 103, contacts 142 of relay 140, line 144, contact bar 145 of drum controller E, line 171, contacts 172 of speed selection switch 40, line 174, contacts 168 of relay 167, line 175, contacts 177 of speed selection switch 41, line 225, normally closed contacts 226 of motor control panel 148, line 227, normally closed contacts 202 of relay 201, line 228, operating solenoid 203 of motor control panel 204, line 213, normally closed contacts 190 of relay 151, line 189, normally closed contacts 125 of relay 106, line 152, contacts 143 of change-over switch 32, line 107, contacts 108 of travel limit switch 42, line 109, etc., to line 121.

Energization of the operating solenoid 203 of motor control panel 204 closes the normally open contacts 229, 230, 231, and 232, and opens the normally closed contacts 233. The closing of the normally open contacts 232 establishes a circuit for the operating solenoid 233 of motor control panel 234 from the line 225, through line 235, line 213, etc., closing the normally open contacts 236, 237, 238, and 239. The closing of contacts 229, 230, and 231 of motor control panel 204 and contacts 236, 237, and 238 of motor control panel 234 connects the cut motor 25 to the power lines in such a manner that the motor operates at a different speed, herein referred to as the "fourth" speed. The closing of the normally open contacts 239 of motor control panel 234 maintains the circuit to the operating solenoids 203 and 233 of the motor control panels 204 and 234 energized after the contacts 177 open due to the stop 36 moving away therefrom. The contacts 176 of speed selection switch 41 are in series circuit with the operating solenoid 192 which when energized causes the motor 25 to operate at its "second" speed, and the opening of these contacts prevents energization of the operating solenoid 192 simultaneous with the energization of the operating solenoids 203 and 233 of the motor control panels 204 and 234. Any possibility of the operating solenoid 147 of the motor control panel 148 or the solenoids 211 and 220 of the motor control panels 212 and 221, respectively, being energized simultaneously with the energization of the operating solenoids 203 and 233 of motor control panels 204 and 234, respectively, is prevented in the manner previously pointed out.

The cut motor 25 continues to operate at its "fourth" speed until the travel limit switch 42 is actuated by the stop 43 to open the normally closed contacts 108 thereof and close the normally open contacts 157. The opening of the normally closed contacts 108 of the travel limit switch 42 breaks the circuit to the operating solenoids 203 and 233 of the motor control panels 204 and 234, respectively, whereupon the motor comes to rest. If at any time during the operation of the motor 25 at any of its speeds other than the "first" speed the start button 29 is depressed, the motor will drop back to its "first" speed by virtue of the closing of contacts 124 of relay 106 and the opening of contacts 125 of the same relay. The closing of contacts 124 completes the circuit to the necessary relays, etc., to connect the cut motor 25 to the power

lines in such a manner that it operates at its "first" speed, and the simultaneous opening of the normally closed contacts 125 breaks the circuit to all other relays, etc., as will be apparent from the wiring diagram. The cut motor 25 then continues to operate at its "first" speed until one of the speed selection switches 39, 40, and 41 is actuated by its respective stop, whereupon the motor operates at the selected speed and continues its automatic cycle of operation. Any possibility of energizing the operating solenoids 203, 233, 211, and 220 of the motor control panels 204, 234, 212, and 221, respectively, simultaneously with the operating solenoid 192 of motor control panel 193 is prevented by the normally closed contacts 190 of relay 151, which contacts open along with the closing of contacts 191 which latter contacts energize the operating solenoid 192.

When the drum controller E is turned to its "second" position, the contact bar 145 is connected to line 194. This establishes the operating circuit for solenoid 192 of motor control panel 193 upon the closing of contacts 143 of change-over switch 32 in a manner similar to that previously described with reference to the energization of operating solenoid 147 of motor control panel 148 when the controller E was set in the "first" position. In this event the cut motor 25 operates at its "second" speed throughout the feed portion of the cycle of operations of the machine. After the work has moved past the cutter, the upward movement of the work head is stopped by the actuation of the travel limit switch 42 by the adjustable stop 43. The work is then removed and the work head returned to its starting position in a manner previously described upon depressing the start push button switch 29.

When the drum controller E is rotated to its "third" position, the contact bar 145 is connected to line 205, and, when rotated to its "fourth" position, the contact bar is connected to line 225 causing the operating solenoids of motor control panels 212 and 221, and 204 and 234, respectively, to be energized upon the closing of contacts 143 of change-over switch 32, causing the cut motor 25 to operate at its "third" or "fourth" speed, as the case may be, in a manner similar to that in which it was caused to actuate at its "first" and "second" speeds when the contact bar 145 is connected to the lines 146 and 194, respectively.

Coolant for the tool or cutter is adapted to be supplied by a pump, not shown on the drawings, which pump is driven by an electric motor 240, the operation of which is controlled by a motor control panel 241, the operating solenoid 242 of which is connected in the control circuit previously described in such a manner that the motor 240 operates only while the cut motor 25 is operated. When the operating solenoid 242 of the motor control panel 241 is energized, the normally open contacts 243, 244, and 245 are closed connecting the motor to the power lines and causing the same to operate. A snap switch 246 located on the control panel 100 provides means for preventing operation of the motor 240 when it is desired to operate the cut motor 25 without the coolant motor 240. When the switch 246 is closed, a circuit is established from the line 198 through the switch 246, line 247, operating solenoid 242 of motor control panel 241 to line 152. This circuit is in parallel with the operating solenoid 139 of relay 140 when the contacts 143 of change-over switch 32 are closed.

The connections between the motors and the motor control panels which actuate the same are not referred to herein in detail but are well-known in the art and are shown on the wiring diagram. In the wiring diagram, the leads to the motor 25 are designated by the reference characters 248 to 261, inclusive. The leads to the motor 28 are designated by the reference characters 262, 263, and 264 and the leads to the motor 240 by the reference characters 265, 266, and 267. The particular motor control shown herein is claimed in my copending applications Serial Nos. 381,035 and 504,693, filed February 28, 1941, and October 2, 1943, respectively, the latter of which applications is a division of the former.

From the foregoing description of the preferred embodiments of the invention, it will be apparent that the objects heretofore enumerated and others have been accomplished and that applicant has provided a novel and improved machine, method, and cutter for cutting or turning metal, plastics, and the like. While the preferred embodiments of the invention have been described with considerable detail, it will be apparent that the invention is not limited to the particular constructions shown and referred to. Alternative constructions and uses will be apparent to those skilled in the art to which the invention relates and it is my intention to hereby cover all adaptations, modifications, alternative constructions, and uses which come within the spirit and scope of the invention as defined in the appended claims.

Having thus described my invention, I claim:

1. In a machine of the character described, the combination of a frame, a work spindle rotatably supported by said frame, said work spindle including means for rotatably supporting a work blank, a tool spindle rotatably supported by said frame with its axis of rotation angularly disposed to and offset from the axis of rotation of the work spindle, a tool having an arcuate shaped cutting edge or portion offset from the plane of the axis of rotation of the work spindle perpendicular to the axis of rotation of the tool spindle and having a radius equal to or substantially equal to the offset between the axis of rotation of the tool and work spindle, said tool having a radially extending top rake angle, means for rotating said work spindle, means for producing a relative feed movement between said work spindle and said tool spindle in a direction generally longitudinally of the axis of rotation of the work blank, and means for rotating said tool spindle.
2. In a machine of the character described, the combination of a frame, a work spindle rotatably supported by said frame, said work spindle including means for rotatably supporting a work blank, a tool spindle rotatably supported by said frame with its axis of rotation angularly disposed to and offset from the axis of rotation of the work spindle, a frusto-conical sector-like tool having cutting edges or portions along the arcuate part thereof of greatest radius, said cutting edges or portions being offset from the plane of the axis of rotation of the work spindle perpendicular to the axis of rotation of the tool spindle and having radii equal to or substantially equal to the offset between the axis of rotation of the tool and work spindles, said tool having a top rake angle extending radially on the axis of rotation of the tool, means for rotating said work spindle, means for producing a relative movement between said work spindle and said

tool spindle whereby a relative feed movement between the tool carried by the tool spindle and the work blank is produced longitudinally of the axis of rotation of the work blank, and means for rotating said tool spindle at variable speeds during said relative movement between said spindles longitudinally of the axis of rotation of the work spindle.

3. The method of cutting metal and the like which comprises rotating a work blank to be formed or cut in cutting relationship with a tool comprising a body portion having an arcuate shaped cutting edge or portion and so positioned with respect to the work blank that a plane at right angles to the axis of rotation of the tool and passing through a cutting edge or portion thereof in contact with the work blank is substantially tangent to the work blank, producing a relative feed movement between the work blank and tool longitudinally of the axis of rotation of the work blank, and rotating the tool about its axis.

4. The method of cutting metal and the like which comprises rotating the work blank to be formed in cutting relationship with a tool comprising a body portion having an arcuate edge provided with axially offset cutting edges or portions adapted to produce portions of different diameter on the work blank and so positioned with respect to the work blank that a plane at right angles to the axis of rotation of the tool and passing through a cutting edge or portion thereof in contact with the work blank is substantially tangent to the work blank, producing a relative feed movement between the work blank and tool longitudinally of the axis of rotation of the work blank, and rotating the tool in predetermined timed relation to the relative feed movement.

5. The method of cutting metal and the like which comprises rotating a work blank to be formed in cutting relationship with a tool comprising a frusto-conical body portion having an arcuate edge provided with axially offset cutting edges or portions adapted to produce portions of different diameter on the work blank, said tool being so positioned with respect to the work blank that a plane at right angles to the axis of rotation of the tool and passing through a cutting edge or portion thereof in engagement with the work blank is substantially tangent to the work blank at said point of engagement, producing a relative feed movement between the work blank and the tool longitudinally of the axis of rotation of the work blank, and rotating the tool in timed relation to the relative feed movement therebetween and the work.

6. The method of cutting metal and the like which comprises rotating a work blank to be formed in cutting relationship with a rotatable tool comprising a body portion having an arcuate shaped cutting edge or portion, said tool being so positioned with respect to the work blank that a plane at right angles to the axis of rotation of the tool and passing through the point of contact between the tool and the work blank is substantially tangent to the latter, producing a relative feed movement between the tool and the work blank longitudinally of the axis of rotation of the work blank, and continuously rotating the tool in timed relation to the relative feed movement therebetween and the work.

7. The method of cutting metal and the like which comprises rotating a work blank to be formed in cutting relationship with a rotatable tool comprising a frusto-conical body having an

arcuate shaped cutting edge or portion, said tool being so positioned with respect to the work blank that a plane at right angles to the axis of rotation of the tool and passing through the part of the cutting edge or portion in engagement with the work at any particular time is substantially tangent to the work blank, producing a relative feed movement between the tool and the work blank longitudinally of the axis of rotation of the work blank, and continuously rotating the tool in timed relation to the relative feed movement therebetween and the work.

8. The method of cutting metal or the like which comprises rotating a work blank to be cut or formed in cutting relationship with a rotatable tool comprising a frusto-conical sector-like body portion having the larger arcuate edge thereof provided with axially offset cutting edges or portions adapted to produce portions of different diameter on the work blank, said tool being so positioned with respect to the work blank that a plane at right angles to the axis of rotation of the tool and passing through the point of engagement between the tool and the work blank is substantially tangent to the work blank, producing a relative feed movement between the tool and the work blank longitudinally of the axis of rotation of the work blank, and rotating the tool in timed relation to the relative feed movement therebetween and the work.

9. The method of cutting metal or the like which comprises rotating a work blank to be cut or formed in cutting relationship with a rotatable tool comprising a frusto-conical sector-like body portion having the larger arcuate edge provided with axially offset cutting edges or portions adapted to produce portions of different diameter on the work blank, said tool being so positioned with respect to the work blank that a plane at right angles to the axis of rotation of the tool and passing through the point of engagement of the tool with the work blank is substantially tangent to the work blank, producing a relative feed movement between the tool and the work blank longitudinally of the axis of rotation of the work blank, and continuously rotating the tool in timed relation to the relative feed movement therebetween and the work.

10. The method of cutting metal or the like which comprises rotating a work blank to be cut or formed in cutting relationship with a rotatable tool comprising a frusto-conical sector-like body portion having the larger arcuate edge provided with axially offset cutting edges or portions adapted to produce portions of different diameter on the work blank, said tool being so positioned with respect to the work blank that a plane at right angles to the axis of rotation of the tool and passing through the point of engagement of the tool with the work blank is substantially tangent to the work blank, producing a relative feed movement between the tool and the work blank longitudinally of the axis of rotation of the work blank, and intermittently rotating the tool in timed relation to the relative feed movement therebetween and the work.

11. The method of cutting metal or the like which comprises rotating a work blank to be cut or formed in cutting relationship with a rotatable tool comprising a frusto-conical sector-like body portion having the larger arcuate edge provided with axially offset cutting edges or portions adapted to produce portions of different diameter on the work blank, said tool being so positioned with respect to the work blank that a

plane at right angles to the axis of rotation of the tool and passing through the point of engagement of the tool with the work blank is substantially tangent to the work blank, producing a relative feed movement between the tool and the work blank longitudinally of the axis of rotation of the work blank, and rotating the tool at different speeds but in timed relation to the relative feed movement therebetween and the work.

12. A rotatable tool of the character described comprising a rotatable body portion having an arcuate shaped cutting edge or portion and a radially extending top rake angle, said tool being adapted to be rotated in cutting relation with a rotating work blank in such position that a plane at right angles to the axis of rotation of the tool and passing through a cutting edge or portion thereof in engagement with the work blank is substantially tangent to the latter. 10

13. A rotatable tool of the character described comprising a rotatable frusto-conical body portion having an arcuate shaped cutting edge or portion and a top rake angle produced by said conical shape, said tool being adapted to be rotated in cutting relation with a rotating work blank in such position that a plane at right angles to the axis of rotation of the tool and passing through a cutting edge or portion thereof in engagement with the work blank is substantially tangent to the latter. 20

14. A tool of the character described comprising a rotatable frusto-conical sector-like body portion having cutting edges or portions along the arc of greatest radius, said tool having a radially extending top rake angle and being adapted to be rotated in cutting relationship with a rotating work blank in such position with respect to the work blank that a plane at right angles to the axis of rotation of the tool and passing through a cutting edge or portion thereof in engagement 40 with the work blank is substantially tangent to the work blank.

15. A tool of the character described comprising a rotatable body portion having axially offset arcuate shaped cutting edges or portions adapted to produce portions of different diameter on a work blank, said tool having a radially extending top rake angle and being adapted to be rotated in cutting relationship with a rotating work blank in such position that a plane at right angles to the axis of rotation of the tool and passing through a cutting edge or portion in engagement with the work blank is substantially tangent to the latter. 5

16. A tool of the character described comprising a sector-like body portion having axially offset cutting edges or portions along the arcuate edge thereof adapted to produce portions of different diameter on a work blank, said tool having a radially extending top rake angle and being adapted to be rotated in cutting relationship with a rotating work blank in such position with respect to the work blank that a plane at right angles to the axis of rotation of the tool and passing through a cutting edge portion in engagement with the work blank is substantially tangent to the latter. 15

20 17. A tool of the character described comprising a sector-like body portion having an axially beveled circumference part and cutting edges or portions along the arcuate edge of greatest radius, a plurality of said cutting edges or portions being axially offset with respect to each other and adapted to produce portions of different diameter on a work blank, said tool having a radially extending top rake angle and being 30 adapted to be rotated in cutting relationship with a rotating work blank and positioned with respect to said work blank in such manner that a plane at right angles to the axis of rotation of the tool and passing through a cutting edge portion in contact with the work blank is substantially tangent to the work blank. 35
